UNITED STATES PATENT OFFICE

AUGUSTUS C. DURDIN, JR., OF CHICAGO, ILLINOIS

VACUUM CONDENSATION PUMP

Application filed February 23, 1928. Serial No. 256,164.

This invention relates to vacuum condensation pumps, and its principal object is to prevent waste of water and to prevent the burning out of the electric motor which is usually employed for driving the pump. Pumps of this character are frequently employed for withdrawing water, vapors, gases and other condensates from steam heating systems and returning the water back to the boiler or some other place.

One of the difficulties encountered in vacuum pumping apparatus of this character is that of preventing wastage of water owing to the fact that air and gases must be separated from the water before the water is returned to the boiler, and oftentimes during the operation of the apparatus, water escapes with the air and other gases and, consequently, becomes lost. In accordance with the present invention, all of the water is conserved, and, furthermore, the vacuum pump is relieved of the heavy duty of increasing the vacuum beyond that required for withdrawing the condensates from the steam heating system.

With such objects and advantages in view, this invention consists in a vacuum condensation pump embodying a tank or reservoir in which the water, air and other condensates are received, a vacuum pump and a water pump, and means controlled by the level of the water contained in the tank for interrupting the flow of condensates to the tank until the level of the water in the tank has been lowered, or, in other words, until the water pump is able to discharge surplus water from the tank as rapidly as water and other condensates enter the tank.

It further consists in a vacuum condensation pump in which the inlet to the vacuum pump has a valve controlled port capable of communicating with the outer atmosphere, whereby in case the liquid in the tank reaches a high level the vacuum in the inlet to the vacuum pump is broken, thereby permitting the pump to operate without creating any suction in the return pipe of the heating system. The invention further consists in the several novel features of construction, ar-

rangement, and combinations of parts hereinafter fully set forth and claimed.

The invention is clearly illustrated in the drawings accompanying this specification in which—

Figure 1 is a vertical longitudinal section taken through a vacuum condensation pump embodying a simple form of the present invention;

Fig. 2 is a vertical cross section taken on the line 2—2 of Fig. 1;

Fig. 3 is a vertical cross section taken on the line 3—3 of Fig. 2;

Fig. 4 is a fragmentary vertical section illustrating a slightly modified form of the invention; and

Fig. 5 is a fragmental vertical section illustrating another modification of the invention.

Referring to said drawings, and first to Figs. 1 to 3 inclusive, which illustrate a simple embodiment of the present invention, the reference character 5 designates a tank or reservoir open to the atmosphere, as through an air outlet port 6 in the upper end thereof. Said tank is adapted to receive water, gases and other condensates from a heating system or other steam plant, and a conduit 7 is shown through which said water, air and other condensates are delivered to the tank. A check valve 8 is usually employed in the conduit 7 which permits the fluid to flow toward the tank, but prevents any return of the fluid towards the system. In some situations the conduit 7 may lead from a receiver, as is well understood by those skilled in the art to which this invention pertains, or the conduit may comprise the return pipe of a steam heating system.

Associated with the tank 5, and discharging into the interior thereof, is a vacuum pump 9 which has an inlet passage 10 communicating with the conduit 7 through a port 11, which, under normal conditions, is open, but is arranged to be closed by a valve 12 whenever the water enters the tank 5 faster than it can be discharged therefrom when a predetermined high level therein is reached. If desired, the casing 13 of the vacuum pump may be formed integral with the tank 5 and

the pump may be contained within the tank.

The tank and pump casing may be composed of upper and lower sections 14 and 15 bolted together along a horizontal plane extending through the axis of the pump shaft 16. This construction facilitates the assembly and disassembly of the structure. The shaft 16 extends out through the walls of the tank and is journaled in suitable bearing boxes 17 carried by the walls of the tank. A suitable electric motor is provided for rotating the shaft, as is well understood. To guard against leakage, stuffing boxes 18 are provided around the shaft at the places where the shaft passes through the tank wall.

As a preference, the vacuum pump is in the form of a rotary or centrifugal pump of the hurling or throwing water type employing an impeller 19 which rotates in the chamber of the pump casing 13 and contains the usual spiral blades and passageways 19^a extending from its interior to its exterior, through which passageways air and water are thrown outward from the internal side of the impeller. Hurling or throwing water is admitted from the tank to the water inlet side 20^a of the pump, and separate alternately arranged passageways 21 and 22 are provided in a cylindrical member 20 which lead from the inlet passage 10 and from the interior of the tank 5 to the interior of the impeller.

As shown, the member 20 has liquid passageways 21 therethrough leading from the interior of the tank to the interior of the impeller, and combined air and liquid passageways 22 leading from the inlet passage 10 to the interior of the pump impeller. These passageways are separated by the walls of the member 20. It is understood that during the rotation of the pump impeller, hurling or throwing water enters the spiral passageways in the impeller and is thrown outward, thereby causing a partial vacuum in the combined air and fluid passageways thus producing the necessary vacuum for exhausting the water, air, and other condensates from the heating system. The casing 13 of the vacuum pump is in the form of an ordinary volute from which the water, air and other condensates are discharged from the vacuum pump into the interior of the tank 5.

Associated with the vacuum pump and tank is a water pump 23 which, in the form shown, comprises a casing 24, preferably cast integral with the tank 5 and casing 13 of the vacuum pump, and an impeller 25 mounted on the pump shaft 16. The inlet to the water pump is shown at 26 and opens from the interior of the tank. The water pump is of the ordinary rotary or centrifugal type and discharges water through discharge opening 27 from which the water may be conducted back to the boiler or to any other place where it is desired to discharge it.

65 The tank being open to the outer atmos-

phere, air and gases entering the tank arise to the surface of the water delivered into the tank and escape through the air outlet opening 6. Water, freed from said gases, enters the inlet 26 of the water pump 23 and is discharged back to the boiler or other place. It frequently happens that the water pump is unable to discharge the water from the tank 5 as rapidly as it accumulates therein above a predetermined high level, and means are provided for temporarily interrupting the flow through the port 11 and into the vacuum pump whenever the liquid in the tank 5 reaches such predetermined high level, and, at the same time, establishing communication between the interior of the tank and the inlet passage 10 to the vacuum pump, whereby the vacuum pump will circulate water through the tank at atmospheric pressure, and consequently the vacuum pump motor will not be subjected to injurious working conditions as would occur in case it were building up an abnormal vacuum or creating a high pressure in the tank.

In the form of the preferred means for accomplishing this result a port 28 is provided between the inlet passage 10 to the vacuum pump and the interior of the tank, which port, under normal conditions, is closed by a valve 29. The valves 12 and 29 are preferably connected so as to move in unison, and, as shown, both valves are mounted upon a common valve stem 30 and connected to one arm 31 of a bell crank lever 32 fulcrumed on a bracket secured to or formed as a part of the casting which forms the tank and pump casings. Upon the other arm 33 of the lever 32 is a float 34. The valve stem 30 has a winged structure 35 surrounding it which forms a slid able connection between the valves and walls that support them, and said winged structure permits the free passage of fluid through the ports whenever the valves are open.

Whenever the water in the tank is at a low level, the float occupies a low position, as indicated by the dotted lines in Fig. 2, and the valve 29 is thereby held closed, whereas the valve 12 is held open, thereby permitting fluid to pass from the conduit 7 through the port 11 and inlet passage 10 to the vacuum pump. Whenever the liquid in the tank reaches a high level, the float is raised to the position shown in full lines in Fig. 2, and the valve 12 is thereby moved to its closed position and the valve 29 moved to its open position, whereby the passage of fluid from the conduit 7 to the vacuum pump is interrupted and the passage through the port 28 from the tank and into the inlet passage 10 is opened.

In the operation of the apparatus, water, air and other condensates from the heating system are drawn into the vacuum pump through the port 11 and inlet passage 10 and are discharged into the interior of the tank

through the volute of the vacuum pump. The air and other gases rise through the water and escape through the air outlet opening 6, and the liquid, which is discharged into the tank, enters the water pump through the intake opening 26 and is discharged through the discharge opening 27 to the boiler, or other place where it is desired to deliver the water. Some of the liquid enters the vacuum pump through the water inlet side 20^a, as has been explained. Whenever the liquid in the tank rises to a predetermined high level, the float is lifted and the valve 12 is moved to its closed position and the valve 29 is moved to its open position, whereby the passage from the conduit 7 to the inlet opening 10 is closed and the passage from the tank 5 to the inlet passage 10 is opened.

Liquid contained in the tank above the port 28 is free to pass through said port and into the inlet passage 10 of the vacuum pump and it enters the impeller thereof and is discharged through the volute back into the tank, and this operation continues so long as the level of the liquid in the tank remains high enough to keep the valve 29 open. Inasmuch as the tank is open to the outer atmosphere, the vacuum in the inlet passage 10 and vacuum pump is broken, and, consequently, it may continue to operate without building up any abnormal vacuum, or creating pressure within the tank, or causing any abnormal strain on the pump motor itself. As soon as the water pump discharges enough water from the tank to allow the float to close the valve 29 and open the valve 12, the port 28 to the inlet passage 10 is closed and communication is again established between the vacuum pump and the conduit 7, whereupon suction is again created in the conduit and water and other condensates contained therein are discharged into the tank.

In the modified form illustrated in Fig. 4, the parts are substantially the same as those shown in the other figures, except that the valve 29 is omitted, the valve 12 being retained as before. In place of the valve 29, a relief valve 29^a is provided which is connected to the inlet passage 10 by a pipe 29^b. The relief valve 29^a is set so as to establish communication between the inlet passage 10 and the outer atmosphere whenever the vacuum in the inlet passage exceeds that required for exhausting the water, air and other condensates from the system. In this form of the invention, whenever the liquid in the tank reaches a predetermined high level, the valve 12 is seated, thereby interrupting the flow of liquid from the conduit to the vacuum pump, and when the vacuum in the inlet passage exceeds that normally required, the relief valve 29^a opens, thereby breaking the vacuum in the inlet passage and vacuum pump and relieving the pump motor of any excessive labor.

It has been found that the valve 12 may

be omitted entirely in some situations, and that by making the port 28 of sufficient size, the water may flow from the interior of the tank through the port 28 and into the inlet passage 10 freely enough to prevent the vacuum pump from creating any suction in the return conduit 7. It will be understood that the check valve 8 prevents the return of air and other fluid into the system.

In the modified form of the invention illustrated in Fig. 5, the inlet passage 10' leads to the vacuum pump, as in the other forms described. The port 28' between the inlet passage and interior of the tank or receptacle 5' is normally closed by a valve 29' connected to a float 34' by a lever 32'. The valve 29' remains closed until the liquid in the tank reaches a predetermined high level and raises the float.

The conduit 7' for water, air and other condensates has a check valve 8' therein and connects with the inlet passage through a port 11', which is controlled by a valve 12'. On the stem 32' of the valve 12' is a plunger 34² which is contained in a cylinder 35, and has a head 34³ that is arranged to seat on a seat 34⁴ in the cylinder 35 in one position of the plunger. When the valve 12' is seated, however, the head 34³ remains unseated.

Leading from the end of the cylinder 35, in which the head 34³ is contained, is a vent pipe 36 which communicates with the interior of the tank or receptacle, whereby the pressure in the cylinder 35 remains at atmospheric pressure. With the vacuum pump in operation, a partial vacuum is created in the inlet passage 10' and consequently the plunger 34² is raised and the valve 12' unseated. The instant the plunger is raised, the head 34³ seats and closes the passages through the cylinder.

Water, air and other condensates are drawn into the vacuum pump and discharged into the tank, and the water pump discharges the water as in the other forms, the air escaping through the air discharge outlet. In case, however, water accumulates in the tank faster than the water pump can discharge it, and, as a consequence, raises the float 34', the valve 29' is unseated thereby admitting air to the inlet passage 10' and breaking the vacuum therein. As a result thereof, the plunger 34² falls, thereby closing the valve 12' and preventing the passage of water, air and other condensates to the vacuum pump until the level of the liquid in the tank again falls below the high level. In this form of the apparatus, the valve 12 is controlled by variations in the pressure in the inlet passage to the vacuum pump.

It is apparent that when water, air and other condensates are discharged into the tank faster than the water pump can discharge the water from the tank when it reaches a predetermined high level, communication between the vacuum pump and return conduit is inter-

rupted and remains interrupted until the water pump has lowered the level of the water in the tank to a predetermined low level, during which interval the vacuum pump motor is not subjected to any undue labor, inasmuch as the vacuum at its inlet side is broken. Moreover, while the air and gases are free to escape from the tank, there is no danger that the water will be forced out through the air outlet opening and consequently all of the water entering the tank is conserved.

More or less variation of the exact details of construction is possible without departing from the spirit of this invention. I desire, therefore, not to limit myself to the exact form of the construction shown and described, but intend, in the following claims, to point out all of the invention disclosed herein.

I claim as new, and desire to secure by Letters Patent:

1. In a vacuum condensation pump, the combination of a tank, a return conduit from which water, air, and other condensates are discharged into the tank, a vacuum pump from which liquid is discharged into the tank and having an inlet passage in communication with said conduit, through a port between said inlet passage and conduit, a float operated valve for controlling said port, and having a float controlled by the level of the liquid in the tank, and a water pump having its inlet communicating with said tank and discharging water therefrom.

2. In a vacuum condensation pump, the combination of a tank, a return conduit from which water, air, and other condensates are discharged into the tank, a vacuum pump from which liquid is discharged into the tank and having an inlet passage in communication with said conduit, and there being a port between said inlet passage and tank, a float operated valve for controlling said port, and having a float controlled by the level of the liquid in the tank, and a water pump having its inlet communicating with said tank and discharging water therefrom.

3. In a vacuum condensation pump, the combination of a tank open to the atmosphere, a return conduit from which water, air and other condensates are discharged into the tank, a vacuum pump from which liquid is discharged into the tank and having an inlet passage in communication with said conduit, and there being a port between said inlet passage and tank, a float operated valve for controlling said port, and having a float controlled by the level of the liquid in the tank, and a water pump having its inlet communicating with said tank and discharging water therefrom.

4. In a vacuum condensation pump, the combination of a tank continuously open to the atmosphere, a conduit from which water, air, and other condensates are discharged into said tank, a vacuum pump from which

liquid is discharged into the tank and having an inlet passage in communication with said conduit and having a valve controlled inlet port between its inlet passage and said conduit, said inlet passage being capable of communicating with the outer atmosphere, said pump being arranged to create a partial vacuum in said conduit, and a water pump having its inlet communicating with said tank and discharging water therefrom.

5. In a vacuum condensation pump, the combination of a tank open to the atmosphere, a return conduit from which water, air and other condensates are discharged into the tank, a vacuum pump from which liquid is discharged into the tank and having an inlet passage leading to said conduit, and containing valve controlled ports, one between said inlet passage and the conduit and one between the inlet passage and tank, float operated means having a float controlled by the level of the liquid in the tank, for simultaneously closing said port to the conduit and opening the port to the tank, and vice versa, and a water pump having its inlet communicating with said tank and discharging water therefrom.

6. In a vacuum condensation pump, the combination of a tank open to the atmosphere, a return conduit from which water, air and other condensates are discharged into the tank, a vacuum pump contained in said tank and discharging thereinto, and having an inlet passage leading to said conduit, and containing valve controlled ports, one between said inlet passage and the conduit and one between the inlet passage and tank, float operated means having a float controlled by the level of the liquid in the tank, for simultaneously closing the port between the conduit and inlet passage and opening the port between the inlet passage and tank, and vice versa, and a water pump having its inlet communicating with said tank and discharging water therefrom.

7. In a vacuum condensation pump, the combination of a tank open to the atmosphere, a return conduit from which water, air and other condensates are discharged into the tank, a hydro-turbine vacuum pump from which liquid is discharged into the tank and having an inlet passage leading to said conduit, and a hurling water inlet opening to the interior of the tank, there being valve controlled ports for said inlet passage, one between said inlet passage and the conduit and one between the inlet passage and tank, float operated means having a float controlled by the level of the liquid in the tank for simultaneously closing said port between the conduit and inlet passage and opening the port between the inlet passage and the tank, and vice versa, and a water pump having its inlet communicating with said tank and discharging water therefrom.

8. In a vacuum condensation pump, the combination of a tank open to the atmosphere, a return conduit from which water, air, and other condensates are discharged into the tank, a vacuum pump from which liquid is discharged into the tank and having an inlet passage leading to said conduit, there being a port between said inlet passage and conduit and a port between said inlet passage and tank, float operated valve mechanism having a float controlled by the level of the liquid in the tank for simultaneously closing one port and opening the other, and vice versa, and a water pump having its inlet communicating with said tank and discharging water therefrom.

9. In a vacuum condensation pump, the combination of a tank, a vacuum pump therefrom which liquid is discharged into the tank and having an inlet passage communicating with a return conduit for water, air and other condensates, there being valve controlled ports between said inlet passage and between tank and said inlet passage and conduit, and float operated means having a float controlled by the level of the liquid in the tank for actuating said valves.

10. In a vacuum condensation pump, the combination of a tank open to the atmosphere, a vacuum pump discharging into said tank and having an inlet passage communicating with a return conduit for water, air and other condensates, there being a valve controlled port between the inlet passage to said vacuum pump and the tank, float actuated means having a float controlled by the level of the liquid in the tank for operating said valve, and a water pump within said tank, having an inlet communicating therewith, said pump operating to discharge water from said tank.

11. In a vacuum condensation pump, the combination of a tank open to the atmosphere, a hydro-turbine vacuum pump therein from which liquid is discharged into the tank and having an inlet passage communicating with a return conduit for water, air and condensates, there being valve controlled ports between said inlet passage and tank and between said inlet passage and conduit, float operated means having a float controlled by the level of the liquid in the tank for actuating said valves, and a water pump contained in said tank and having an inlet communicating with said tank, said water pump operating to discharge water therefrom.

12. In a vacuum condensation pump, the combination of a tank structure and a pump structure, the pump structure having a casing formed integral with the tank structure a horizontal pump shaft extending out through the walls of said tank structure, and an impeller mounted on said pump shaft within said casing, said tank and casing being

formed of two sections joined together along a horizontal plane extending through the axis of the pump shaft.

13. In a vacuum condensation pump, the combination of a tank open to the atmosphere, a return conduit from which water, air and other condensates are discharged into the tank, a vacuum pump having an inlet passage leading to said conduit, there being valve controlled ports, one between said inlet passage and the conduit and one between the inlet passage and tank, means controlled by the level of the liquid in the tank for simultaneously closing said port to the conduit and opening the port to the tank, and vice versa, and a water pump having its inlet communicating with said tank and discharging water therefrom.

14. In a vacuum condensation pump, the combination of a tank open to the atmosphere, a return conduit from which water, air and other condensates are discharged into the tank, a vacuum pump contained in said tank and discharging thereinto, and having an inlet passage leading to said conduit, there being valve controlled ports, one between said inlet passage and the conduit and one between the inlet passage and tank, means at least one of which is controlled by the level of the liquid in the tank for simultaneously closing said port to the conduit and opening the port to the inlet passage, and vice versa, and a water pump having its inlet communicating with said tank and discharging water therefrom.

15. In a vacuum condensation pump, the combination of a tank, a return conduit from which water, air and other condensates are discharged into the tank, a vacuum pump from which liquid is discharged into the tank and having an inlet passage in communication with said conduit, through a port between said inlet passage and conduit, a valve for controlling said port, automatically operating means for actuating said valve, and a water pump having its inlet communicating with said tank and discharging water therefrom.

16. In a vacuum condensation pump, the combination of a tank, a return conduit from which water, air, and other condensates are discharged into the tank, a vacuum pump from which liquid is discharged into the tank and having an inlet passage in communication with said conduit, there being a valve controlled port between said inlet passage and tank, a valve controlled port between said conduit and inlet passage and automatically operated valve actuating mechanism at least one of which is controlled by the level of the liquid in the tank for the valves of both ports, and a water pump having its inlet communicating with said tank and discharging water therefrom.
